UNITED STATES PATENT OFFICE.

ELIJAH F. STEELE, OF WALLINGFORD, CONNECTICUT.

RUNNING-GEAR FOR AUTOMOBILES.

SPECIFICATION forming part of Letters Patent No. 687,667, dated November 26, 1901.

Application filed May 4, 1901. Serial No. 58,743. (No model.)

To all whom it may concern:

Be it known that I, ELIJAH F. STEELE, of Wallingford, in the county of New Haven and State of Connecticut, have invented a new Improvement in Running-Gear for Automobiles; and I do hereby declare the following, when taken in connection with the accompanying drawings and the numerals of reference marked thereon, to be a full, clear, and exact description of the same, and which said drawings constitute part of this specification, and represent, in—

Figure 1, a plan view of one form which a running-gear constructed in accordance with my invention may assume, portions of the vehicle-wheels being broken away; Fig. 2, a view in front elevation of the front-wheel frame and the gears connected therewith; Fig. 3, an enlarged broken view, in vertical section, on the line *a b* of Fig. 1, showing the antifriction-rollers employed in the connections between the wheel-frames and the vehicle-wheels to prevent the cramping of the parts; Fig. 4, a detail view, in horizontal section, on the line *c d* of Fig. 3; Fig. 5, a detached view, in side elevation, of one of the wheel-axes; Fig. 6, a plan view thereof; Fig. 7, a broken view, in side elevation, of the running-gear with the near vehicle-wheels removed, illustrating the connection of the steering-handle with the front and rear wheel frames; Fig. 8, a broken view, in vertical section, on the line *e f* of Fig. 1, with the rear wheels removed; Fig. 9, a broken view, in vertical section, on the line *g h* of Fig. 1; Fig. 10, a diagrammatic view of such a differential gear as may be employed; Fig. 11, a detached plan view of the front-wheel frame; Fig. 12, a view thereof in front elevation; Fig. 13, a reverse plan view thereof; Fig. 14, a view in vertical cross-section on the line *i j* of Fig. 13.

My invention relates to an improvement in running-gear for automobiles, the object being to provide for such vehicles, whatever power they may employ, simple, compact, and durable running-gear constructed with particular reference to the most economical utilization of power and to its quick response and accommodation to the wide range of varying conditions met with in driving and steering an automobile through city streets and alleys and over country highways and roads.

With these ends in view my invention consists in a running-gear having certain details of construction and combinations of parts, as will be hereinafter described, and pointed out in the claims.

As herein shown, my improved running-gear is constructed with reference to positively driving all four of the vehicle-wheels and to positively steering with all of the said wheels; but, if desired, I may leave off the driving connections of the two front wheels and positively drive the two rear wheels and steer with all four wheels, or I may positively drive with two wheels and steer with two wheels. These suggested changes involve merely omissions of parts, and hence do not require illustration or further description.

In carrying out my invention I employ a rectangular main frame 2 of any suitable form and construction and provided at its front end with a platform 3, from the forward end of which depends a journal-box 4, having a cap 5 and receiving the forward trunnion 6 of the tilting forward-wheel frame 7, the tubular rear trunnion 8 of which is received by a journal-box 9, having a cap 10, as clearly shown in Fig. 9. Under this construction provision is made for the tilting action of the front-wheel frame without disturbing the position of the main frame 2, which remains horizontal while either end of the said wheel-frame is lifted—as, for instance, by irregularities in the road or by the running of one or the other of the front wheels over stones or other obstructions. The rear end of the main frame 2 is solidly secured to the rear-wheel frame 11 by means of bolts 12, furnished with nuts 13 and passing through tubular posts 14, which rest upon the frame 11, and which in turn have the rear end of the frame 2 rested upon them; but other means may be provided for rigidly securing the rear end of the frame 2 to the rear-wheel frame 11.

To provide for positively driving the two front wheels 15 and 15^a, I employ a main driving or power shaft 17, located centrally below the main frame 2 and extending parallel therewith. At its forward end this shaft 17 extends through the tubular trunnion 8 of the rocking or tilting wheel-frame 7, as shown in Fig. 9. Under this construction the trun-

nions 6 and 8 are located in the same axial line with the driving-shaft 17, which carries the power to the front vehicle-wheels 15 and 15^a and to the rear vehicle-wheels 16 and 16^a. 5 Now as the said trunnions and the said shaft have the same axial center it will be obvious that the rocking or tilting of the wheel-frame 7 on its said trunnions will in no wise affect the direct transmission of the power to the two front vehicle-wheels through the said shaft 17, which is entirely unaffected by the position of the wheel-frame 7 with respect to the main frame 2.

The forward end of the shaft 17 is provided 15 with a bevel-pinion 18, located within an opening 19, formed within the large central portion or body 20 of the wheel-frame 7. The trunnions 6 and 8, already described, project from opposite points on the front and rear 20 walls of the said wheel-frame body 20. The said bevel-pinion 18 meshes into a corresponding pinion 21, also located within the opening 19 and mounted upon one end of a sleeve 22, which is rigidly secured to the section 23 25 of the divided front shaft and which receives the other section 23^a of the said shaft. The two sections 23 and 23^a of the said shaft are coupled together by differential gearing 24 of any approved construction, as shown in 30 Fig. 10.

Inasmuch as differential gears are well understood both as to their construction and operation, it has seemed unnecessary to show and describe herein such gears in detail; but it is 35 to be said that differential gears of some sort—as, for instance, those shown in Fig. 10—are employed to couple together the adjacent sections 23 and 23^a of the sectional front shaft. Under ordinary conditions these gears are at 40 rest and virtually act as a rigid coupling. When, however, as in turning or cramping the vehicle, one wheel is caused to move faster than the other, the differential gear is brought into play and permits one of the two 45 sections 23 23^a to remain at rest or to move faster than the other section on the well-known principle of differential gearing.

The sections 23 and 23^a of the front shaft are located in deep longitudinal grooves 24^a, 50 formed in the under face of the front-wheel frame 7, and are held in place in the said grooves by means of small blocks 25, secured to the frame by means of nuts 26; but these blocks may be replaced by any other equivalent devices.

The outer ends of the shaft-sections 23 and 23^a are provided with bevel-pinions 27, which are housed, as it were, in depending vertically-arranged triangular skeleton heads 28, formed 60 integral with and located at the outer ends of the wheel-frame 3, below the upper face of which they depend. The said pinions 27, which are located in vertical planes, mesh into horizontally-arranged bevel-pinions 29, which 65 in turn mesh into bevel gear-wheels 30, rigidly secured to the inner faces of the vehicle-wheels 15 15^a, with the pivotal axles 31 of

which they are concentric. The said axles 31 are pivotally connected with the main frame 2, so as to permit the vehicle-wheels to be 70 swung in vertical planes, as required for steering the automobile. Obviously the vertical axes on which the wheel-axes turn must coincide with the axes on which the bevel-pinions 29 turn, so that as the vehicle-wheels are 75 swung around in steering the gear-wheels 30, rigidly attached to them, may ride, as it were, upon the bevel-pinions 29 at the same time the same are transmitting power to the vehicle-wheels for driving the automobile. 80

In order to prevent cramping in the connections between the front-wheel frame and the rear-wheel frame and the vehicle-wheels, I construct those connections so as to include antifriction instrumentalities. (Shown in one 85 form in Figs. 3 and 4.) In carrying out this part of my invention I locate the shaft 32 of each of the pinions 29 within an upper series of antifriction-rollers 33 and a lower series of antifriction-rollers 34, separated from 90 each other by a ring 35, interposed between their adjacent ends. These rollers, which are in direct contact with the shaft 32, are also in direct contact with a vertically-arranged steel bearing-case 36, formed at its upper 95 end with a flange 37, upon which the hub 29^a of the bevel-pinion 29 rests. Each of the chambered heads 28 has its upper arm 38 formed with an opening 39 for the reception of the upper end of the said case 36 and its 100 lower arm 40 formed with a corresponding opening 41 for the lower end of the said case. The said lower end of the case is internally threaded for the application to it of a threaded head 42, which bears against the lower 105 face of the arm 40 and forms a bearing for a nut 43, applied to the lower end of the shaft 32, which extends down through the case and projects below it. The antifriction-rollers 33 and the antifriction-rollers 34 are therefore 110 interposed directly between the shaft 32 and the case 36 inclosing it. The outer surface of the said case 36 forms a bearing for a set of antifriction-rollers 44, concentric with the rollers 33, and a corresponding set of rollers 115 44^a, concentric with the rollers 34, the rollers 44 and 44^a being separated from each other by a ring 44^b, corresponding to the ring 35. The rollers 44 and 44^a are confined in place 120 by and coat directly with the inner surface 120 of the axle-sleeve 45, which is vertically arranged and which corresponds in length to the height of the space 45^b between the arms 38 and 40 of the head 28. It will be understood, of course, that the shaft 32, the case 36, and 125 the axle-sleeve 45 are concentrically arranged.

It will be readily understood that under the foregoing construction the four sets of rollers will effectually prevent any tendency of the shaft 32 or axle-sleeve 45 to cramp 130 owing to weight imposed upon the connections or to any other causes.

Under the construction just described the front vehicle-wheels 15 15^a and the rear ve-

hicle-wheels 16 16^a are free to be swung in vertical planes, as required for steering, and positively driven at the same time, for the reason, as aforesaid, that the vertical axes 5 through which their pivotal axes are connected with the main frame 2 are coincident with the vertical axes of the shafts of the pinions 29, through which the power for positively driving the vehicle-wheels is transmitted to them.

The main driving or power shaft 17 may be driven by power of whatever character—that is to say, power supplied by a gasoline-engine, by steam, electricity, compressed air, 15 compressed liquid, carbonic-acid gas, and so on. The power, however derived, is in the construction shown designed to be applied through a shaft 47, mounted in suitable bearings depending from the main frame 2. This 20 shaft is furnished with a pinion 48, meshing into a gear-wheel 49, mounted on a shaft 50; also journaled in suitable bearings depending from the said frame 2 and furnished at its inner end with a bevel-pinion 51, which 25 meshes into two corresponding gear-wheels 52 and 53, loosely mounted upon the said power-shaft 17 and coupled therewith through a sliding clutch 54, located between the said gear-wheels 52 and 53 and feathered upon 30 the said shaft 17 and provided at its forward end with a coupling-pin 55, adapted to be entered into a hole 56, formed in the wheel 52, and provided at its rear end with a coupling-pin 57, entering a hole 58, formed in the 35 wheel 53. This clutch is formed with two collars 59 and 60, receiving between them a shifter 61, constructed in any desired manner and secured to an operating-slide 62, mounted at its ends upon cross-bars 2^a 2^a of 40 the main frame 2, the said slide being limited in its movement by its provision with slots 63, receiving screws 64, entering the bars 2^a 2^a. When the slide is moved to the limit of its forward movement, the clutch 54 will be coupled with the wheel 52, whereby the power-shaft 17 will be rotated for driving the vehicle 45 forward. When, on the other hand, the slide 62 is moved to the limit of its rearward excursion, the clutch 54 will be coupled with 50 the wheel 53, and the vehicle will be reversed or driven rearward. When the slide is in its intermediate position, neither of the wheels 52 53 will be coupled with the clutch, whereby the power will be entirely cut off from the 55 vehicle for stopping it without stopping the motor, for coasting without stopping the motor, for coasting when the motor is stopped, and for other kindred uses and contingencies; but of course the means shown for applying 60 power to the power-shaft 17 and for rotating that shaft in one direction or the other or cutting out the power from connection with it may be very widely changed without departing from my invention. What I wish to emphasize is that power may be positively supplied to all of the vehicle-wheels or to only one

pair of them and that its transmission to them is neither interrupted nor affected by their movement in vertical planes for the purpose of steering.

For steering the vehicle I provide it, as herein shown, with a hand-lever or manual 7c 65, located upon a shaft 66, journaled in the main frame 2, and provided at its lower end with a worm 67, meshing into a worm-gear 68, 75 mounted upon a steering-shaft 69, extending parallel with the power-shaft 17 and journaled in bearings depending from the said main frame 2. The said shaft 69 is provided at its rear and forward ends with depending 80 crank-arms 70, connected by links 71 with transversely-arranged steering-bars 72, the opposite ends of which are pivotally connected with steering-arms 73, forming extensions of the bearing-collars 45 of the pivotal wheel- 85 axles 31, the steering-arms of the wheel-axes of the two forward wheels 15 and 15^a being parallel with each other and extending rearward and the corresponding steering-arms of the axles of the two rear wheels 16 and 16^a 90 being parallel with each other and extending forward.

It will be apparent that when the lever 65 is turned the steering-shaft 69 will be rotated in one direction or the other and produce lateral movement in both of the steering-bars 72, which will move in the same direction and which in turn will cause corresponding movements of the vehicle-wheels, all of which will be moved at the same time and to the 100 same extent and without interfering with the positive transmission of power to them, as already described. This is obviously a very advantageous construction and arrangement, as it makes the steering of the vehicle simple 105 and reliable, for the reason that the rear wheels are compelled to track with the front wheels, so that anything that the front wheels miss the rear wheels will miss instead of hit, which is likely to result when the rear wheels 110 are not in steering controlled synchronously with the front wheels.

It is obvious that the particular means for applying power to the power-shaft and reversing the same and cutting out the power 115 therefrom may be readily varied, and the same is true of the means employed for steering. If it is desired to positively drive only two wheels, the driving connections of the front wheels will be left off in building the 120 machine, which when so constructed may be steered with all four wheels or with only the two front wheels. So, too, other means than shafts and gears and pinions, such as chains or belts, might be used to positively drive the 125 vehicle-wheels, or different ways of driving them by gears might be employed, and the same is true of the steering means, which may be replaced by other instrumentalities for the same purpose. I would therefore have it understood that I do not limit myself to the 130 construction and arrangement as herein de-

scribed, but hold myself at liberty to make such changes as fairly fall within the spirit and scope of my invention.

Having fully described my invention, what I claim as new, and desire to secure by Letters Patent, is—

1. In running-gear for automobiles, the combination with a main frame, of a front-wheel frame pivotally connected with the main frame so as to have a tilting action in a vertical plane with respect thereto, a rear-wheel frame connected with the said main wheel,

10 two front vehicle-wheels and two rear vehicle-wheels, axles for the said wheels connected with the said frames and turning on vertical axes, and power connections for positively driving the said wheels, including a centrally-arranged power-shaft extending at its rear end to the rear-wheel frame, and extending at its forward end into the front-wheel frame, and having its axis coincident with the axis on which the same swings vertically with respect to the main frame.

2. In running-gear for automobiles, the combination with a main frame, of a front-wheel frame pivotally connected therewith so as to have a tilting action in a vertical plane

25 with respect thereto, a rear-wheel frame, two front and two rear vehicle-wheels, axles connected with the said front and rear wheel frames and turning on vertical axes, and power connections for positively driving the said vehicle-wheels, including a centrally-arranged power-shaft extending at its rear end 30 to the rear-wheel frame, and at its forward end into the front-wheel frame, and also including divided shafts and differential gearing located in each of the said wheel-frames.

3. In running-gear for automobiles, the combination with a main frame, of a front-wheel frame pivotally connected therewith and having a tubular trunnion, of a power-shaft extending through the said trunnion into the said wheel-frame, two vehicle-wheels respectively connected with the said wheel-frame, and means for transmitting the power of the said shaft to the said wheels.

4. In running-gear for automobiles, the combination with a main frame, of a front-wheel frame pivotally connected therewith, a rear-wheel frame attached thereto, vehicle-wheels respectively connected with the ends of the said wheel-frames, and power connections for positively driving the said vehicle-wheels, including a centrally-arranged power-shaft extending rearward to the rear-wheel frame, and extending forward into the front-wheel frame through the rear trunnion of the pivotal connection between it and the main frame.

5. In running-gear for automobiles, the combination with a main frame provided at its forward end with two depending journal-boxes, of a front-wheel frame provided with 65 a forward and a rear trunnion respectively received by the said boxes, the rear trunnion being tubular, whereby the front-wheel frame

is connected with the main frame so as to have tilting action in a vertical plane with respect thereto, vehicle-wheels pivotally connected with the ends of the said frame, and power connections for positively driving the said vehicle-wheels, including a power-shaft entering the said front-wheel frame through the tubular rear pinion thereof, whereby the 75 tilting of the frame does not disturb the transmission of power to the wheels.

6. In running-gear for automobiles, the combination with the main frame thereof, of a wheel-frame adapted to be connected with the main frame, and formed at its ends with depending skeleton heads, vehicle-wheels, axles therefor entering the said heads with which they are pivotally connected on vertical axes, and power connections for positively driving the said wheels, including gearing located in the said heads.

7. A wheel-frame for running-gear for automobiles, having a large central portion or body formed with an opening for the reception of gearing, and formed at its ends with skeleton heads for the reception of the pivotal axles of the wheels and of gearing for driving the same.

8. In running-gear for automobiles, the combination with a main frame, of wheel-axes pivotally connected therewith so as to turn on vertical axes, and each provided with a steering-arm, a pair of front vehicle-wheels, a pair of rear vehicle-wheels applied to the said axles, a steering-bar connecting the steering-arms of the front axles, a steering-bar connecting the steering-arms of the rear axles, a steering-shaft mounted in the wheel-frame, and provided at its rear and forward ends with depending crank-arms connected with the said steering-bars, a worm-gear mounted upon the said shaft, and a hand lever or manual mounted in the said main frame, and provided with a worm meshing into the said worm-gear, whereby all of the vehicle-wheels are simultaneously moved to the same extent in steering the machine.

9. In running-gear for automobiles, the combination with the main frame thereof, of a front-wheel frame and a rear-wheel frame, each provided at each end with a skeleton head, wheel-axes, each having a centrally-arranged axle-sleeve entering the respective heads, a vehicle-wheel applied to each axle, gear-wheels secured to the respective vehicle-wheels, pinions meshing into the said gear-wheels, shafts on which the said pinions are mounted, and which are arranged concentrically with the sleeves of the respective 125 axles, bearing-cases mounted in the said skeleton heads and receiving the said shafts, and roller-bearings interposed between the said shafts and said cases, and between the said cases and the said sleeves.

10. In running-gear for automobiles, the combination with a main shaft, of a front-wheel frame pivotally connected with the forward end of the main frame so as to swing in

a vertical plane, and provided at its ends with skeleton heads, a rear-wheel frame attached to the rear end of the main frame and provided at its ends with skeleton heads, 5 wheel-axes pivotally connected with the said heads, so as to swing on vertical axes, power connections for positively driving the vehicle-wheels, including a centrally-arranged power-shaft extending rearward to the center 10 of the rear-wheel frame, and extending forward into the front-wheel frame, and also including gearing located in each of the said

frames and in the heads thereof; and steering connections with the said axles, whereby the wheels may be swung with respect to the said 15 wheel-frames for steering the vehicle.

In testimony whereof I have signed this specification in the presence of two subscribing witnesses.

ELIJAH F. STEELE.
